UNITED STATES PATENT OFFICE

HERBERT S. JANDUS, OF DETROIT, MICHIGAN, ASSIGNOR TO GENERAL SPRING BUMPER CORPORATION, OF DETROIT, MICHIGAN, A CORPORATION OF MICHIGAN

DESIGN FOR AN IMPACT BAR FOR AUTOMOBILE BUMPERS

Application filed February 6, 1933. Serial No. 47,121. Term of patent 7 years.

To all whom it may concern:

Be it known that I, HERBERT S. JANDUS, a citizen of the United States, and a resident of the city of Detroit, in the county of Wayne and State of Michigan, have invented a new, original, and ornamental Design for an Impact Bar for Automobile Bumpers, of which the following is the specification, reference being had to the accompanying drawing, forming a part thereof.

In the drawing:

Figure 1 is a front view of the impact bar.
Figure 2 is a plan view of the impact bar.
Figure 3 is an end view of the bar taken from the left hand side of Figure 1.

I claim:

The ornamental design for an impact bar for automobile bumpers as shown.

HERBERT S. JANDUS.
